FOREIGN PATENT DOCUMENTS

CN 308940596 * 11/2024

Primary Examiner — Rachel A. Voorhies*Assistant Examiner* — Benjamin D. Wannemacher(74) *Attorney, Agent, or Firm* — MUNCY, GEISSLER,
OLDS & LOWE, P.C.(57) **CLAIM**

The ornamental design for a ratchet wrench as shown and described.

DESCRIPTION

FIG. 1 is a top, front, and right perspective view of a ratchet wrench showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a top, front and right perspective view showing the ratchet wrench in use.

The broken lines in the drawings illustrate portions of the ratchet wrench which form no part of the claimed design.
